UNITED STATES PATENT OFFICE.

EDWARD A. LANGENBACH, OF CANTON, OHIO.

DESIGN FOR A METALLIC CEILING-PLATE.

SPECIFICATION forming part of Design No. 24,487, dated July 16, 1895.

Application filed June 3, 1895. Serial No. 551,575. Term of patent 7 years.

To all whom it may concern:

Be it known that I, EDWARD A. LANGENBACH, a citizen of the United States, and a resident of Canton, county of Stark, State of Ohio, have invented a new and useful Design for Metallic Ceiling-Plates, of which the following is a full, clear, and exact description, reference being had to the accompanying drawings, making part of this specification.

- 10 My design relates to metallic ceiling-plates. In the accompanying drawings, Figure 1 represents a ceiling or finishing plate made in accordance with my design. Fig. 2 is a section of one of the plates.
- 15 My design consists essentially of an ornamental plate comprising the ribs A, connected together to form a square or rectangle formed with rectangular rosettes or figures B, intermediate their ends, with a circular projection
- 20 C in the center formed with radiating triangular-shaped projections D. At the meeting ends of the ribs comprising the square are ornamental rosettes E, and radiating there-

from are a number of ornamental projections F. Inclosed within the square is an ornamental circle in relief, and intersecting with the rectangular figures B are ornamental segmental ribs G. In the spaces between said segments and circles are a number of ribs I, with ornamental scrollwork K in relief. Located centrally in the square is an ornamental rosette L, having radiating therefrom a number of leaf-shaped projections M. The segments and also the projections M are formed with a number of projections or beads O.

What I claim is—

The design for a metallic ceiling plate herein shown and described.

In testimony whereof I have hereunto set my hand this 17th day of May, A. D. 1895.

EDWARD A. LANGENBACH.
